UNITED STATES PATENT OFFICE.

THOMAS EUBANK, OF LITTLE ROCK, ARKANSAS, ASSIGNOR TO THE MISSOURI RAILWAY EQUIPMENT COMPANY, OF ST. LOUIS, MISSOURI.

AUTOMATIC HAND-BRAKE-RELEASE MECHANISM.

SPECIFICATION forming part of Letters Patent No. 591,666, dated October 12, 1897.

Application filed June 14, 1897. Serial No. 640,784. (No model.)

To all whom it may concern:

Be it known that I, THOMAS EUBANK, a citizen of the United States, residing at the city of Little Rock, in the county of Pulaski, State 5 of Arkansas, have invented certain new and useful Improvements in Automatic Hand-Brake Releases, of which the following is a full, clear, and exact description, reference being had to the accompanying drawings, forming part of this specification, in which—

Figure 1 is a partial bottom plan view of a railroad-car, showing the usual brake levers and rods of an air-brake system with my automatic hand-brake-releasing mechanism 15 connected thereto. Fig. 2 is a similar view of the mechanism immediately connected to the brake-cylinder, showing in dotted lines the effect of the initial movement of the piston of the brake-cylinder on the automatic 20 hand-brake-releasing mechanism before the brakes are applied. Fig. 3 is a side elevational view of the brake-cylinder, illustrating the manner of connecting the brake and releasing levers to the fork of the piston. Fig. 25 4 is a detail view of the dog, showing its manner of releasing the ratchet-wheel of the hand-brake staff. Fig. 5 is a side elevational view of said dog and its operating-lever.

This invention relates to a new and useful 30 improvement in means for automatically releasing hand-brakes on passenger or freight cars when said cars are provided with air-brakes. Railroads experience considerable trouble and wear of wheels on rolling-stock 35 from hand-brakes on cars being left set by trainmen when switching cars into trains or sidings, who neglect to release or let the hand-brakes off. Passengers also carelessly turn the hand-brakes while on the platforms of 40 coaches, and trainmen being in other parts of train overlook such setting of the hand-brakes. When hand-brakes are set in air-brake systems, the application of air by the engineer in making a stop to set the brakes 45 causes the brake-shoes to bind on the wheels and the wheels to slide on the rails, making flat faces. It follows, therefore, that the hand-brakes must be released before air is

applied to set the brakes. Otherwise it is impossible to prevent the wheels from sliding 50 on the rails, which causes considerable damage and often necessitates delays. Manually-set brakes is the only feature in air-brake systems over which the engineer has not complete control, such being left to the train 55 crew. The train crew cannot possibly watch all the hand-brakes on passenger-coaches, even by the most diligent attention, unless the number of the crew was greatly increased for that purpose. 60

The object of my invention is to automatically release manually-set brakes no matter how tightly the same may be set and place the same under complete control of the engineer. This object I accomplish by the mechanism hereinafter described, which when the 65 engineer applies air to set the brakes the hand-brakes must first be released before the air in the brake-cylinders affects the brakes.

In the accompanying drawings I have illustrated the common form of air-brake mechanism to which I have applied my invention, but it is obvious that there are other forms of brake mechanism to which my invention would be equally applicable, and also that 70 there are changes in the construction, arrangement, and combination of the several parts of my device which could be made and substituted for those herein shown and described without in the least departing from 75 the nature and principle of my invention.

In the drawings, 1 indicates the brake-cylinder; 2, the fork on the end of the piston-rod; 3 and 4, the cylinder-levers; 5, cylinder-lever tie-rod; 6 and 7, cylinder-lever and 80 floating-lever tie-rods; 8, floating lever; 9, hand-brake connecting-rod; 10, upper brake-lever connecting-rod; 11, lower brake-lever connecting-rod; 12 and 13, live and dead truck-levers, respectively; 14, ratchet-wheel 85 on hand-brake staff, upon which is wound chain on end of hand-brake connecting-rod, and 15, dog for preventing return movement of ratchet-wheel on hand-brake staff when same is set, said parts being of any ordinary 90 or approved construction, except cylinder-

lever 3, which has a slot-and-pin connection with the piston-rod fork instead of being positively connected thereto, as heretofore.

My improved hand-brake-releasing mechanism consists of a lever A, slotted at a to receive its pivot-bolt to accommodate itself to movement of piston-fork 2, to which it is positively connected.

B indicates a connecting-rod secured to end 10 of lever A and running to one end of car, where it is connected to a lever C, fixed to the dog 15, which coöperates with the ratchet-wheel of the brake-staff.

B' indicates a rod secured to lever A on the 15 opposite side of fulcrum of said lever from rod B, said rod B' running to opposite end of the car and coöperating with dog in like manner as rod B.

D indicates a stop preferably adjustable 20 relative to stroke of piston in brake-cylinder, said stop being mounted in nose of brake-cylinder and coöperating with slotted end of lever 3, as shown in Fig. 3.

Assuming the hand-brakes to be set at one 25 or both ends of the car and the dogs 15 in engagement with the ratchet-wheels on the staffs of said hand-brakes, the first operation upon application of air behind piston in brake-cylinder is to force said piston outwardly, and 30 lever A being positively connected thereto will move therewith, drawing rods B and B' toward center of car, and by the connection between said rods and the dogs 15 through lever C will cause said dogs to be disengaged 35 from their coöperating ratchet-wheels on the brake-staffs, thus releasing the brakes which have been set manually. This release of the manually-set brakes is accomplished during what I term an "initial" movement of the 40 piston in the brake-cylinder, because said cylinder while performing such work is carrying the pin which passes through its cross-head or fork along the slot in lever 3 and will not become positively connected with said lever 3 until said pin has traversed the slot, when the brakes will be applied as usual.

From the above description it will be noted that no matter how many cars have hand-brakes set with one or two turns on brake-staff or as tight as the brakes can be set by hand when the engineer applies the brakes through the air system the initial travel of the piston before it is even engaged with the air-brake mechanism releases the hand-brakes, 50 after which the air-brakes are set in the same stroke and without requiring any extra manipulation of the engineer's valve by the engineer or attention on the part of the train crew to the hand-brakes. The engineer has 55 thus complete control over the entire train irrespective of whether the hand-brakes are set or not, and flat faces or sliding of the wheels may be entirely prevented. The mechanism is entirely automatic in its action—that is, it performs its work, when it has work

to do, without relying upon any one to assist or direct it in its action.

Having thus described my invention, what I claim, and desire to secure by Letters Patent, is—

1. The combination with the air-brake mechanism of passenger or freight cars, of means operated by said air-brake mechanism to automatically release the manually-set brakes; substantially as described. 75

2. The combination with the air-brake mechanism of passenger or freight cars, of means connected to and operated by said air-brake mechanism to automatically release manually-set brakes before said air-brake mechanism becomes operative; substantially as described. 80

3. The combination with the air-brake mechanism of passenger or freight cars in which is included a brake-cylinder and its piston, of means connected to and operated by said piston for automatically releasing manually-set brakes before said piston is operative relative to the air-brake mechanism; substantially as described. 85

4. The combination with the air-brake mechanism of a passenger or freight car, in which mechanism is included a cylinder and piston, a lever connected to and operated by said piston, and a connection between said lever and the retaining pawl or dog which co-90 operates with the ratchet-wheel of the hand-brake staff; substantially as described.

5. The combination with a cylinder and its piston, of a hand-brake mechanism comprising suitable means for applying and retaining power, and a connection between said piston and the retaining device for the hand-brake mechanism; substantially as described. 95

6. The combination with the brake-staff 105 and its ratchet-wheel, of a dog for coöperating with said ratchet-wheel, a cylinder and piston, and a connection between said piston and said dog; substantially as described.

7. The combination with the cylinder and its piston, of suitable brake mechanism which is operated by said piston after the same has traveled some distance on its stroke, and a hand-brake-releasing mechanism connected to and operated by said piston when the same 115 is making its initial movement, or before said piston operates the brake mechanism; substantially as described.

8. The combination with the cylinder and piston, of a brake mechanism in which is included a slotted lever 3, a stop for arresting said lever so that the first movement of the piston will be the distance of said slot before said piston becomes positively connected with the brake mechanism, and means operated 125 by said piston during such initial movement to effect the release of the brakes, should they be manually set; substantially as described.

9. The combination with the brake-cylinder 130

der and its piston, of brake mechanism in which is included a slotted lever for coöperating with the piston, an adjustable stop on said cylinder for arresting the slotted end of said lever, a lever A positively connected to said piston, said lever A being slotted for the passage of its fulcrum-pin, and rods B and B' connected to said lever A and to the dogs which coöperate with the ratchet-wheels on

the brake-staffs at the ends of the car; substantially as described.

In testimony whereof I hereunto affix my signature, in presence of two witnesses, this 24th day of May, 1897.

THOS. EUBANK.
